UNITED STATES PATENT OFFICE.

HENRY HEUER, OF COBB, WISCONSIN.

HARVESTER.

Application filed September 13, 1924. Serial No. 737,527.

This invention relates to harvesters and is designed particularly for harvesting pea vines.

It is an object of the invention to provide a structure which can be drawn over a field and will quickly cut the vines, direct them onto suitable conveyors, and deliver the vines to a wagon adjacent the machine so that, at no time during the operation, will the vines come into contact with the ground and become dirty.

A further object is to provide a machine of this character which is compact in construction, will operate efficiently, and will greatly reduce the cost of harvesting peas.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings the preferred form of the invention has been shown.

In said drawings,

Figure 1 is a front elevation of the machine, the draft tongue being in section.

Fig. 2 is a rear elevation.

Fig. 3 is a vertical transverse section.

Fig. 4 is an enlarged view partly in elevation and partly in section of a portion of the drive mechanism.

Fig. 5 is a plan view of the mechanism shown in Fig. 4.

Fig. 6 is a detail view of another portion of the driving mechanism.

Referring to the figures by characters of reference 1 designates the main supporting wheel journaled in one side of a laterally extending frame 2 of any desired construction, the other side of the frame being supported by a wheel 3. This frame has a draft tongue 4 extending forwardly therefrom adjacent the wheel 1. A sickle bar 5 is mounted for reciprocation along the front of the frame and is the same as commonly employed in harvesters, the sickle bar being indicated at 5 and being driven by a pitman 6 connected to the wrist pin 7 of a disk 8. This disk is secured to one end of a shaft 9 on the rear portion of which is mounted a sprocket 10. A pin 11 is also secured to the shaft and meshes with a pinion 12 se-

cured to a shaft 13 which is provided with a sprocket 14. This sprocket receives motion through a chain 15 from a large sprocket 16 which rotates with the wheel 1. Thus 60 it will be seen that as the machine moves forwardly motion will be transmitted from the wheel 1 to the sickle bar so that the vines in the path of the bar will be severed. As shown particularly in Fig. 1, gathering 65 fingers 17 may be extended forwardly from the frame 2 adjacent the end of the sickle bar.

Extending upwardly from that side of the frame 2 in which wheel 1 is journaled, is a 70 supporting frame 18 on which is mounted an inclined structure 19 extending downwardly through the frame 2 and upwardly and laterally beyond the side of said frame.

Journaled within the frame 2 at the lower 75 end of the structure 19 is roll 20 and another roll 21 is journaled in the frame 2 close to the wheel 3, as shown at 21. On these two rolls is mounted an endless apron 22 adapted to receive the vines after they have been 80 severed by the sickle bar 5. Another roll 23 is journaled in the lower portion of the structure 19 and is engaged by an endless apron 24 extending upwardly and laterally within the structure 19 and having its upper 85 portion mounted on a roll 25. This roll 25 is connected, at its back end, to a sprocket 26 engaged by an endless chain 27 which extends under and is adapted to be driven by the sprocket 10. Said chain also extends 90 over an idler sprocket 28 and thence into engagement with a sprocket 29 rotatable with the roll 20. Chain 27 also extends into engagement with an idler 30. Thus it will be seen that when the machine moves forward the apron 22 will be driven in the direction indicated by the arrow in said figure.

Journalized in the structure 19 above the apron 24 are upper and lower rolls 31 carrying an endless apron 32. This apron acts 95 as a retaining means for holding vines on the apron 24 while they are being carried upwardly by said apron.

An endless delivery conveyor 33 is mounted within the upper portion of the structure 105 19 and extends from a point close to the upper portion of apron 24 outwardly to a point close to the end of the structure 19. This apron is mounted on rolls 34 and 35 and is so positioned that the vine, when delivered from apron 24, will pass onto the conveyor 33.

Rotatable with the roll 25 and located at the front of the structure 19 is a gear 36 which meshes with a gear 37 connected to and rotatable with the upper roll 31. Another gear 38 is rotatable with the gear 37 and meshes with a gear 39 connected to and rotatable with the roll 34. Thus it will be seen that when sprocket 26 is driven by the forward movement of the machine, motion will be transmitted therefrom through the roll 25 to gear 36, thence to gears 37 and 38 and to gear 39 with the result that the apron 32 and the conveyor 33 will be driven in the directions indicated by the respective arrows.

Rotatable with the gear 36 is a pinion 40 which meshes with a smaller pinion 41 secured to a downwardly and laterally inclined shaft 42. This shaft is supported in a tubular arm 43 suitably connected to the supporting structure 18 and the lower end of the shaft is provided with a pinion 44. This pinion meshes with another pinion 45 secured to a shaft 46 which is journaled in a frame 47 carried by the structure 18 and which can be mounted in any suitable manner. The said frame 47 has a shaft 48 journaled therein and extending laterally therebeyond, this shaft being provided with a reel 49 adapted to work close to the apron 22 and extending practically throughout the length of the apron. A sprocket 50 is secured to the shaft 48 and receives motion through a chain 51 from a sprocket 52 journaled on the lower forward portion of the frame 47. Another larger sprocket 53 rotates with the sprocket 52 and receives motion through a chain 54 from a smaller sprocket 55 secured to the shaft 46.

40 A seat for the driver may be provided at any suitable point, as shown at 56 adjacent the various control levers of the machine indicated generally at 57 and which do not

constitute any part of the present invention.

It will be apparent from the foregoing description that, when the machine is drawn forwardly, the various parts will be set in motion by the rotation of the wheel 1. The sickle bar 5 will cut the vines in the path thereof, and these vines will fall upon the moving apron 22. This apron will convey the vines laterally to the apron 24 which will draw the vines between said apron and the apron 32, the said aprons cooperating to carry the vines upwardly and deposit them upon the conveyor 33. This conveyor, in turn, will discharge the vines onto a wagon at the side of the harvester. The wheel 49 serves to throw the cut vines back onto the apron 22.

60 What is claimed is:—

In a harvester of the class described, the combination with a main supporting wheel and a laterally extending frame supported at one end thereby, an endless apron moving from one side to the other of the frame, a sickle bar mounted for reciprocation in front of the apron, and a reel mounted for rotation above the sickle bar; of a structure extending over and laterally beyond the main supporting wheel upper and lower endless aprons for elevating material delivered from the apron on the first named frame, a longitudinal shaft supported by said structure at the outer side of the main wheel, means for transmitting motion from one end of said shaft to the sickle bar, means for transmitting motion from the other end of said shaft to the aprons, and mechanism for transmitting motion from the aprons to the reel.

75 In testimony that I claim the foregoing as my own, I have hereto affixed my signature.

HENRY HEUER.
